Filed May 9, 1966, Ser. No. 548,514
7 Claims. (Cl. 49—449)

ABSTRACT OF THE DISCLOSURE

A latching and locking device for horizontally movable, bypassing sliding doors, comprising a latch element pivotable about a vertical axis in a slot in one of the doors and insertable into another slot in the other door to latch the two doors together against relative horizontal and relative vertical movement. The latch element may be locked in its inserted position.

Summary and objects of invention

The present invention relates to a sliding-door latching and locking device and primary objects of the invention are to provide a device which permits the door to move freely between its open and closed positions, which include means for latching the door in its closed position automatically upon movement of the door into its closed position, which includes means for locking the door in its closed position, and which includes means for locking the door against removal from its track means when it is locked in its closed position.

Another primary object of the invention is to provide a device usable with bypassing sliding doors which permits free movement of both doors between their closed and open positions, which automatically latches both doors together in their closed positions upon movement thereof into their closed positions, which locks both doors together in their closed positions, and which locks both doors against removal from their respective track means when they are locked together in their closed positions.

Since the invention is particularly applicable to the bypassing sliding doors of show cases, it will be considered in connection therewith for convenience. However, it will be understood that the invention may be used in connection with bypassing sliding doors in other environments, and may, in some instances, be used in conjunction with single doors.

Considering the invention more specifically now, important objects thereof are to provide a showcase, or other structure, which includes: parallel first and second track means; first and second bypassing sliding doors respectively movable along the first and second track means; first and second latch elements respectively carried by the first and second doors and interengageable when the doors are in their closed positions, the second latch element preferably being formed by a latch recess in the second door into which the first latch element is insertable to lock the doors together when the doors are in their closed positions; means mounting the first latch element on the first door for movement between an extended position, wherein it is insertable into the latch recess when the doors are in their closed positions, and a retracted position; means biasing the first latch element toward its extended position so that it automatically tends to enter the latch recess in the second door when the doors are in their closed positions to lock the two doors together; means for locking the first latch element in its retracted position to prevent engagement thereof with the latch recess in the second door when the two doors are in their closed positions; means for locking the first latch element in its extended position when the doors are closed and the first latch element is inserted into the latch

2

recess in the second door, such locking means preferably being key operated so that the doors cannot be unlocked for movement to their open positions without the necessary key; and means on the first door and operable concurrently with the locking means last mentioned for interlocking the first door and the first track means so that the doors are locked together and interlocked with the first track means against lateral removal of the doors from their track means when the doors are closed and locked together by the first latch element on the first door and the latch recess in the second door.

With the foregoing construction, the latching and locking device of the invention performs four important functions, as follows:

First, by locking the first latch element in its retracted position, the latching device of the invention is rendered inoperative. Consequently, the showcase may be opened and closed by the sales person in charge thereof without any interference by the device of the invention.

Second, by leaving the first latch element free to move into its extended position under the influence of its biasing means, the showcase doors are automatically latched in their closed positions upon movement thereof into such positions. This is very desirable to minimize the possibility of shoplifting in the event that the sales person in charge has to leave the showcase unattended, as while waiting on a customer some distance away. Stores find that if the doors of showcases containing relatively small and valuable articles are left unlatched or unlocked while such showcases are unattended, shoplifting losses are high since it is a simple matter for a shoplifter to reach over the top of the showcase, slide one of the doors open, remove one or more articles from the top shelf of the showcase by reaching over the top thereof, and escape undetected. The present invention minimizes the possibility of shoplifting losses of this nature by providing means for automatically latching the showcase doors in their closed positions upon closure thereof.

Third, by actuating the key-operated locking means for locking the first latch element in the latch recess with the doors closed, the doors cannot be opened by anyone not having the necessary key. Thus, the showcase can be locked against entry by unauthorized persons, as when closing the store for the night.

Fourth, since the aforementioned key-operated locking means also locks the first door to its track means, as well as locking the two doors together, the showcase cannot be entered by removing one or both doors from the corresponding track means. Consequently, the showcase is positively locked against anything but forcible entry.

Other important objects of the invention are to provide a latching and locking device of the foregoing nature wherein: the first latch element is pivotally mounted in a slot through the first door for pivotal movement, about a pivot axis parallel to the plane of the first door and perpendicular to the direction of movement thereof, between an extended position at an acute angle to the first door and a retracted position parallel to and within the first door; wherein the latch recess in the second door is a latch slot adapted to receive the first latch element when the doors are in their closed positions; and wherein the locking means for locking the first latch element in its extended and retracted positions and for locking the first door to its track means are all disposed within the first door and are actuated by a single key-operated lock located substantially entirely within the first door. A related object is to provide a construction wherein the locking means for the first latch element comprise a locking element mounted within the first door for rotation between operative and inoperative positions and engageable

with opposed surfaces of a locking projection on the first latch element when in its operative position to lock the first latch element in its retracted and extended positions, respectively.

The foregoing construction provides a very compact latching and locking device all moving parts of which are located substantially entirely within the first door, which is an important feature of the invention. A related object is to provide a latching and locking device all moving parts of which are mounted substantially entirely within the bottom rail of a glass showcase door, thereby providing a very inconspicuous installation readily accessible only to authorized persons, and inaccessible to potential shoplifters from the front of the showcase.

The foregoing objects, advantages, features and results of the present invention, together with various other objects, advantages, features and results thereof which will be evident to those skilled in the art to which the invention relates in the light of this disclosure, may be achieved with the exemplary embodiment of the invention described in detail hereinafter and illustrated in the accompanying drawing.

Description of the drawing

FIG. 1 is a fragmentary isometric view of the rear of a showcase having bypassing sliding glass doors the bottom rails of which incorporate the latching and locking device of the invention;

FIG. 2 is a fragmentary horizontal sectional view taken as indicated by the arrowed line 2—2 of FIG. 1, and showing a first latch element of the invention locked in its extended position to lock the two doors together;

FIG. 3 is a fragmentary vertical sectional view taken as indicated by the arrowed line 3—3 of FIG. 2;

FIG. 4 is a fragmentary vertical sectional view taken as indicated by the arrowed line 4—4 of FIG. 2 and showing locking means in positions to lock the first latch element in its extended position and to lock the doors to their track means;

FIG. 5 is a fragmentary horizontal sectional view similar to FIG. 2, but showing the first latch element locked in its retracted position to permit the doors to be opened and closed freely; and

FIG. 6 is a view similar to FIG. 4, but showing the means for locking the doors to their track means in a position to permit removal of the doors therefrom.

Detailed description of exemplary embodiment of invention

Referring initially to FIG. 1 of the drawing, fragmentarily illustrated therein is a frame 10 for bypassing sliding doors 12 and 14 which may be located at the rear of a showcase, the front of a display cabinet, or the like. For convenience, the doors 12 and 14 will be regarded as located at the rear of a showcase and will be referred to hereinafter as front and rear, or second and first, doors, respectively.

The frame 10 includes an upper rail 16 provided therein with downwardly facing front and rear channels 18 and 20 for the upper edges of the front and rear doors 12 and 14, respectively. The front and rear doors 12 and 14 respectively comprise front and rear glass panels 22 and 24 the respective lower edges of which are disposed in upwardly facing channels 26 and 28 of front and rear lower rails 30 and 32 of the respective doors 12 and 14. The front and rear lower rails 30 and 32 respectively include downwardly facing channels 34 and 36 containing wheels for supporting the respective doors 12 and 14, one of the wheels in the channel 34 being visible in FIG. 1 of the drawing and being designated by the numeral 38.

The front and rear doors 12 and 14 ride on front and rear track means 42 and 44 respectively disposed in front and rear channels 46 and 48 in a lower rail 50 of the frame 10. The track means 42 and 44 respectively include rib-like tracks 52 and 54 on which the wheels on the

doors 12 and 14 run, the wheels being grooved to receive the tracks.

It will be noted that the lower rails 30 and 32 of the doors 12 and 14 are H-shaped and respectively include 5 horizontal webs 56 and 58 respectively separating the upper and lower channels of such rails.

The foregoing structure of the frame 10 and the bypassing sliding doors 12 and 14 is conventional. The present invention resides in means 60 for latching and locking the doors 12 and 14 together in their closed positions, and for locking the doors against lateral removal from their tracks 52 and 54, as will now be described in detail.

The basic component of the latching and locking means 15 or device 60 is a latch element 62 which is carried by the door 14 and which is preferably pivotable into and out of a latch recess 64 in the door 12 when the two doors are in their closed positions. The latch element 62 is pivotable about an axis parallel to the plane of the door 14 and perpendicular to the direction of movement thereof in a manner to be described. When the latch element 62 is in its extended position, shown in FIG. 2, it is disposed at an acute angle to the door 14 and is inserted into the latch recess 64. When the latch element 25 62 is in its retracted position, shown in FIG. 5, it is disposed within and parallel to the door 14.

More particularly, the latch element 62 is a relatively thin, flat, elongated strip disposed in a complementary slot 66 through the bottom rail 32 of the door 14 just 30 below the web 58 thereof. The latch element 62 is pivotally connected intermediate its ends to the web 58 by a pivot 68 oriented to provide the hereinbefore-defined pivot axis. The latch recess 64, which receives one end of the latch element 62 therein when the doors 12 and 14 are closed and the latch element is in its extended position, has the form of a slot in one wall of the channel 34 in the bottom rail 30 of the door 12. The latch slot 35 64 is located just below the web 56 of the rail 30 and registers with one end of the slot 66 when the doors 12 and 14 are closed. The latch slot 64 is complementary to the latch element 62 so that there is a relatively close fit between the upper and lower surfaces of the latch element and the upper and lower edges of the latch slot when the doors are closed and the latch element is extended. Consequently, the two doors 12 and 14 are locked together in the vertical direction so that neither can be lifted without lifting the other. As best shown in FIG. 2, the end of the latch element 62 within the latch slot 64 is engageable with one end of the latch 40 slot to prevent horizontal opening movement of either door. Thus, the latch element 62, when inserted into the latch slot 64, cooperates with the latch slot to lock the two doors together both vertically and in the directions of opening movement of the doors.

In instances where the foregoing vertical interlock of the doors 12 and 14 is not desired, the latch element 62 may be so located that it merely engages the edge 69 of the door 12, instead of entering the latch slot 64. In such a case this slot may be omitted, and the door edge 60 69 acts as a latch element.

The latch element 62 is biased toward its extended position, shown in FIG. 2, by a rattrap spring 70 coiled around a downward extension of the pivot 68. One end of the spring 70 is suitably secured to the latch element 62 at 72, while the other end thereof bears against one 65 wall of the channel 36 at 74. With this construction, as long as the latch element 62 is free to pivot, it will automatically enter the latch slot 64 to latch the doors 12 and 14 closed upon movement thereof into their closed positions. This is an important antishoplifting feature, as hereinbefore outlined.

The latch element 62 is provided thereon, adjacent the end thereof opposite the end insertable into the latch slot 64, with a manual actuator tab 76 projecting rearwardly through the slot 66. As will be apparent, the doors

12 and 14 can be unlatched readily merely by pushing forwardly on the actuator tab 76. The sales person can do this readily with his or her toe if desired, it being unnecessary to bend over to unlatch the doors.

Thus, the invention provides a very simple and positive means for latching the doors 12 and 14 closed automatically upon closure thereof. At the same time, the two doors are positively interlocked both vertically and horizontally in their directions of opening movement. The doors 12 and 14 may be unlatched very simply merely by pushing forwardly on the actuator tab 76.

The invention also provides means 80 for locking the latch element 62 in its retracted position, shown in FIG. 5, to prevent automatic latching of the doors 12 and 14 upon movement thereof into their closed positions. This feature is highly desirable where the showcase is attended by a sales person who finds it necessary to open and close the doors frequently.

Considering the locking means 80 more specifically, it includes an axially-short lock 82 of conventional construction operable by a key 84. The lock 82 is disposed substantially entirely within the bottom rail 32 of the door 14, extending into the interior of such bottom rail through a hole 86 drilled into the rear walls of the channels 28 and 36. The web 58 is also provided with an opening 88 therein in the vicinity of the hole 86 to accommodate the lock 82. The lock is secured in place by clamping the periphery of the hole 86 between two threadedly connected parts of the lock, as will be clear from FIGS. 2, 3 and 5.

Connected to the lock 82 is a locking element 90 which is rotatable from an operative position, shown in FIGS. 2, 4 and 5, to an inoperative position, shown in FIG. 6, upon corresponding rotation of the key 84. Referring to FIG. 5, when the locking element 90 is in its operative position and the latch element 62 is in its retracted position, the locking element 90 engages one edge 92 of a locking projection 94 at the end of the latch element 62 opposite the end thereof which is insertable into the latch slot 64. Interengagement of the locking element 90 and the edge 92 of the locking projection 94, as shown in FIG. 5, locks the latch element 62 in its retracted position. Consequently, under such conditions, the doors 12 and 14 are free to slide between their open and closed positions without interference by the latching and locking device 60 of the invention.

When it is desired to provide for automatic latching of the doors 12 and 14 in their closed positions, the key 84 is turned as required to place the locking element 90 in its inoperative position, as shown in FIG. 6. This releases the latch element 62 so that it is free to enter the latch slot 64 each time the doors 12 and 14 are moved into their closed positions, thereby latching them closed automatically.

Another locking means 96 is provided for locking the doors 12 and 14 in their closed positions whenever locking of the showcase is desired, as when closing the store for the night. The locking means 96 includes the locking element 90 and an edge 98 of the locking projection 94 opposite the edge 92 thereof. More particularly, with the latch element 62 in its extended position wherein it is inserted into the latch slot 64, the key 84 can be turned to position the locking element 90 in engagement with the edge 98 of the locking projection 94, as shown in FIGS. 2 and 4. Under these conditions, the latch element 62 is locked in its extended position to interlock the two doors 12 and 14 in the manner hereinbefore discussed.

Thus, it will be apparent that the locking element 90 can be positioned in its inoperative position, shown in FIG. 6, to permit automatic latching of the doors 12 and 14, or it can be positioned in engagement with the edge 92 of the locking projection 94 to prevent automatic latching, or it can be positioned in engagement with the edge 98 of the locking projection to lock the doors 70 75

closed. This triple function of the locking element 90 is an important feature of the invention.

Considering another important feature, sliding door installations of the nature under consideration must provide clearances between the upper edges of the doors 12 and 14 and their guiding channels 18 and 20 sufficient to permit lifting the doors from their tracks 52 and 54 and out of the frame 10. Because of these clearances, it is conceivable that the doors 12 and 14 might be lifted out of the frame 10 by a thief to provide access to the interior of the showcase, even though the latch element 62 is locked in its extended position by the locking element 90 to interlock the two doors in their closed positions.

To prevent removal of the doors 12 and 14 from the frame 10, even though locked together, the invention provides the lock 82 with a second locking element 100, shown as formed integrally with the locking element 90, which is located forwardly of the track 54 and which depends below the top of such track a substantial distance, as shown in FIGS. 3 and 4, when the locking element 90 is in its operative position. The distance which the locking element 100 depends below the top of the track 54 exceeds the distance that the doors 12 and 14 can be lifted from their tracks 52 and 54 as the result of the clearances provided at the upper edges of the doors.

Consequently, when the latch element 62 is locked in its extended position by the locking element 90 to interlock the doors 12 and 14, the locking element 100 depends below the top of the track 54 sufficiently to prevent laterally rearward removal of the doors 12 and 14 from their tracks 52 and 54. Therefore, unauthorized access to the showcase cannot be achieved by lifting the locked doors 12 and 14 out of the frame 10, which is an important feature of the invention. (In this connection, it will be understood that the frame 10 includes structure, not shown, for preventing laterally forward or inward removal of the doors 12 and 14 when closed.)

When it is desired to remove the doors 12 and 14 from their tracks 52 and 54, the key 84 is turned to place the locking elements 90 and 100 in the positions shown in FIG. 6. The length of the locking element 90 is insufficient to permit it to engage the track 54, so that the door 14 can be removed readily.

Thus, the latching and locking device 60 of the invention achieves its important functions of permitting free movement of the doors 12 and 14 between their closed and open positions, of automatically latching both doors together in their closed positions upon movement thereof into such position, of locking the doors together in their closed positions, and of locking the doors against removal from their respective tracks when they are locked together in their closed positions.

Although an exemplary embodiment of the invention has been disclosed herein for purposes of illustration, it will be understood that various changes, modifications and substitutions may be incorporated in such embodiment without departing from the spirit of the invention as defined by the claims which follow.

I claim as my invention:

1. In combination:
- (a) first and second bypassing sliding doors;
- (b) first and second latch elements respectively carried by said first and second doors and interengageable when said doors are in their closed positions;
- (c) means pivotally mounting said first latch element on said first door for pivotal movement, about a pivot axis parallel to the plane of said first door and perpendicular to the direction of movement thereof, between an extended position, wherein said first latch element is disposed at an acute angle to said first door and is engageable with said second latch element when said doors are in their closed positions, and a retracted position wherein said first latch element is disposed parallel to said first door;
- (d) said first latch element being pivotally mounted

in a slot extending through said first door, and said second latch element being formed by a latch slot in said second door into which said first latch element is insertable to lock said doors together when said doors are in their closed positions and said first latch element is in its extended position; and

(e) means biasing said first latch element toward its extended position.

2. The combination set forth in claim 1 wherein said first latch element is provided with a manual actuator on the side of said first door opposite said second door.

3. The combination set forth in claim 1 including means for locking said first latch element in its retracted position.

4. The combination set forth in claim 3 including means for locking said first latch element in its extended position.

5. The combination set forth in claim 4 wherein said locking means comprise a locking element mounted on said first door for rotation between operative and inoperative positions and engageable with opposed surfaces of a locking projection on said first latch element when in its operative position to lock said first latch element in its retracted and extended positions, respectively.

6. In combination:

(a) parallel first and second track means;
 (b) first and second bypassing sliding doors respectively movable along said first and second track means;
 (c) first and second latch elements respectively carried by said first and second doors and interengageable when said doors are in their closed positions;

(d) means mounting said first latch element on said first door for movement between an extended position, wherein it is engageable with said second latch element when said doors are in their closed positions, and a retracted position;

(e) said second latch element being formed by a latch recess in said second door into which said first latch element is insertable to lock said doors together

5

10

15

20

25

30

when said doors are in their closed positions and said first latch element is in its extended position;

(f) means biasing said first latch element toward its extended position;

(g) means for locking said first latch element in its retracted position;

(h) means for locking said first latch element in its extended position;

(i) means on said first door and operable concurrently with the locking means last mentioned and engageable with said first track means for interlocking said first door and said first track means against lateral removal of said first door from said first track means; and

(j) whereby said doors are locked together and interlocked with said first track means against lateral removal of said doors from said track means when said first latch element is inserted into said latch recess and is locked in its extended position.

7. The combination set forth in claim 6 wherein said first latch element is pivotally mounted in a slot extending through said first door, and wherein said latch recess comprises a latch slot in said second door which is adapted to register with said slot through said first door and into which said first latch element is pivotally insertable.
